ASH TRAY

Harvey Paul Forton, San Lorenzo, Calif.

Application June 13, 1950, Serial No. 167,745

2 Claims. (Cl. 131—235)

1

This invention relates to ash trays, and more particularly to a receptacle for receiving ashes or the like in which a wire insert element is operatively connected to the receptacle.

An object of the present invention is to provide an ash receiver in which means are provided for supporting a burning cigarette or the like in spaced relation to the bottom of the receiver, and which is constructed so as to preclude a burning cigarette from accidentally falling out of the receiver with the attendant fire hazards.

Another object of the invention is to provide an ash tray of the type described in which a cigarette may be supported as aforesaid, the said supporting means permitting even burning of the cigarette for the entire length of the latter.

A further object of my invention is to provide an ash receiver of the character above set forth in which the cigarette supporting portion may be readily inserted in or removed from the receiver so as to simplify cleaning of the parts.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to the drawings:

Figure 1 is a cross sectional view of the ash tray of the present invention, the plane of view being taken substantially along the line 1—1 of Figure 2.

Figure 2 is a top plan view of the ash tray.

Figure 3 is a side elevational view, portions of the figure being broken away in order to more clearly disclose the features of construction.

The ash receiver or tray, generally indicated by the numeral 6, may possess any desired ornamental or utilitarian shape, but as here shown, comprises a generally circular bottom 7, an integral side wall 8 rising generally vertically therefrom, and an open top 9, the receiver, as will be understood, being arranged to receive ashes or cigarette butts after the cigarettes have been smashed by a user. The receiver 6 may be constructed from any desired material, such as metal, wood, or a thermoplastic material. However, a burning cigarette placed in direct contact with a wood or plastic receptacle will deleteriously affect the latter, and therefore means must be provided for substantially preventing extended periods of engagement therebetween.

2

In accordance with the teachings of the present invention, such means preferably includes a basket-like element, generally denoted by the numeral 11, such element being disposed entirely within the tray so as to prevent accidental dislodgment of a burning cigarette from the tray. Also, the basket 11 is arranged to support a cigarette at a plurality of spaced points so as to insure free air circulation around the entire length of the latter while maintaining the same spaced from the bottom and side walls of the tray. The basket element 11 is preferably constructed from a single piece of wire, one end 12 of the latter being formed substantially as a circle and supported by a shelf 13 formed in side wall 8 by a counterbore 14 adjacent the upper end of the receptacle. The wire, after following the shelf for substantially a complete revolution, is bent radially inwardly at 16, and thereafter is coiled as a downwardly convergent helix having substantially evenly spaced convolutions and terminating in a cylindrically coiled portion 17 which is telescopically engaged on a post member 18 extending vertically upwardly from the center of the receptacle bottom.

With the arrangement as above described, it will be apparent that the basket element may be removed from the tray 6 by merely sliding the same upwardly over the post 18, and likewise may be reinserted in an operative position by a reverse procedure. It will be noted that the outermost coil of the helix is spaced sufficiently from the wire end 12 and the side wall 8 so that if desired, a cigarette may be placed directly into the ash receiver without placing it on the basket element. Due to the conical shape of the element 11, a cigarette placed thereon will normally repose with its burning end extending inclined downwardly into the tray, but, of course, with such end being spaced from the tray bottom. Depending on the exact positioning of the cigarette on the element 11, two or more coils of the helix will support the cigarette, but as the contact area between the wire and cigarette is negligible, there will be substantially no interference with air circulation around the cigarette, and complete and even burning of the same will ensue.

If desired, the side wall 8 of the receptacle, may be radially enlarged as indicated at 21 to compensate for the material removed by the counterbore 14, and also, it may be desirable to provide the upper end of post 18 with a conical recess 22 to facilitate snuffing the lit end of a cigarette. In any event, the cigarette holder and ash tray above described will insure the maintenance of

a cigarette out of contact with the receptacle proper or the retention of butts and ashes disposed therein, will eliminate the danger of a cigarette falling out of the tray, will permit easy cleaning of the tray, and will permit a cigarette to burn evenly and thereby reduce the distasteful odors occasioned by smoldering or partially burning discarded cigarettes.

I claim:

1. An ash tray having a flat bottom and a vertically disposed wall having a recess in the upper edge and in the inner surface of the wall, said recessed walls surrounding the flat bottom, post means extending upwardly from the center of said bottom, and a cigarette rest in the form of a basket comprising a single piece of wire having plural vertically superposed coils having a diameter slightly larger than the post and adapted to fit thereover, rest on the bottom of the tray and to cover the lowermost portion of the post, a series of relatively close equally spaced coils forming an upwardly and outwardly directed spiral adapted to support a cigarette and extending toward the recess in the side wall, a final coil of said wire substantially circular in form and extent adapted to rest in said recess, and a portion of said wire joining the end of the outermost turn of the spiral and said final coil, said portion being substantially perpendicular to the outermost spiral and to said final coil and having a length adapted to provide a space between the spiral and the wall such that a cigarette may be supported on said spiral and cigarette butts may be placed in the ash tray between the spiral and the final coil.

2. An ash tray having a flat bottom and a vertically disposed wall having a recess in the upper edge and in the inner surface of the wall, said recessed wall surrounding the flat bottom, a vertically disposed cylindrical post extending upward-

ly from the center of the bottom to a height less than that of the recessed wall, the top of the post having means adapted to receive the lit end of a cigarette to extinguish the same, and a cigarette rest in the form of a basket comprising a single piece of wire having plural vertically superposed coils having a diameter slightly larger than the post and adapted to fit thereover, rest on the bottom of the tray and to cover the lowermost portion of the post, a series of relatively close equally spaced coils forming an upwardly and outwardly directed spiral adapted to support a cigarette and extending toward the recess in the side wall, a final coil of said wire substantially circular in form and extent adapted to rest in said recess, and a straight upwardly and radially outwardly extending portion of said wire joining the end of the outermost turn of the spiral and said final coil, said outwardly extending portion being substantially perpendicular to the outermost spiral and to said final coil and having a length adapted to provide a space between the spiral and the wall such that a cigarette may be supported on said spiral and cigarette butts may be placed in the ash tray between the spiral and the final coil.

HARVEY PAUL FORTON.
